UNITED STATES PATENT OFFICE

163,723

PORTABLE CRANE

Harry P. Vischer, Brooklyn, Mich.

Application October 31, 1947, Serial No. 142,240

Term of patent 14 years

(Cl. D14—3)

To all whom it may concern:

Be it known that I, Harry P. Vischer, a citizen of the United States, and resident of Brooklyn, in the county of Jackson and State of Michigan, have invented a new, original, and ornamental Design for a Portable Crane, of which the following is a specification, reference being had to the accompanying drawings, forming a part thereof.

In the drawings, Fig. 1 is a side perspective view of a portable crane, showing my new design, and Figs. 2 and 3 are front and rear perspective views thereof, respectively.

The dominant features of my design are shown

by means of full lines in the drawing, the dotted line illustration of the truck being for illustrative purposes only.

I claim:

The ornamental design for a portable crane, substantially as shown and described.

HARRY P. VISCHER.
